UNITED STATES PATENT OFFICE.

ARTHUR L. DUNCAN AND CHARLES E. FORRY, OF OAKLAND, CALIFORNIA.

CAN SOLDER HORN.

Application filed March 16, 1921. Serial No. 452,648.

To all whom it may concern:

Be it known that we, ARTHUR L. DUNCAN, and CHARLES E. FORRY, citizens of the United States, residing at Oakland, in the 5 county of Alameda and State of California, have invented new and useful Improvements in Can Solder Horns, of which the following is a specification.

This invention relates to can forming machinery, and particularly pertains to a solder horn, upon which the body portions of the can are formed.

It is common practice to provide can body forming machines with floating horns, 15 over which the cylindrical bodies may be positioned and carried longitudinally thereof, and it is the principal object of the present invention to provide a support for the horn, which will insure that the horn is at 20 all times supported, while permitting the cans to move without interruption therealong without damage to the lap of the can body due to the weight of the horn.

The present invention contemplates the 25 use of a horizontally disposed horn operatively positioned relative to suitable feed means, by which a succession of can bodies may be moved along the horn and a rotary support adapted to contact with the horn at 30 points between the cans and to thereby insure that the horn will be at all times supported.

The invention is illustrated by way of example in the accompanying drawings, in 35 which:

Figure 1 is a fragmentary view showing the present invention.

Fig. 2 is an end view showing the arrangement of parts of the present invention.

Referring more particularly to the drawings, 40 10 indicates a bed plate supported at its opposite ends by legs 11, one set of which is not indicated in the drawings. Standards 12 extend upwardly from the bed plate and 45 carry sprocket shafts 13. These shafts are fitted with sprockets 14 over which a sprocket feed chain 15 is led. The chain 15 is formed with flights 16, which are mounted upon certain of the links of the chain, 50 and are disposed in equal spaced relation to each other. It is to be understood that the length of the bed plate and the distance from the center to center of the sprocket wheels may be as desired.

The lower run of the sprocket chain moves 55 horizontally and parallel to a solder horn

17. This horn is connected at one end to a can body forming machine, and its opposite end is allowed to float without rigid support. Cylindrical can bodies 18 are 60 adapted to move longitudinally of the horn and are fed therealong by engagement with the flights 16. This horn is formed with spaced vertical plates 19, between which is disposed an arcuate track section 20, which 65 will be hereinafter described. On the outer faces of the plates 19 side members 21 are secured. These members have outer arcuate faces disposed to substantially conform to the inner circumference of the can bodies 18 70 moving therealong.

In order to continuously support the outer end of the horn at the same time to permit the cans to move therealong without interruption, a star wheel 22 is provided. This 75 wheel is provided with a plurality of radial arms 23, here shown as six in number. The number of these arms and their angular relation to each other will depend upon the length of the can bodies and their spaced 80 relation to each other while moving along the horn. The star wheel is mounted upon a shaft 24, journaled on the bed plate 10 and disposed at right angles to the longitudinal axis of the horn. The outer ends of the radial arms 23 are fitted with rollers 25 carried on pins 26. The rollers move in the same plane with the longitudinal axis of the horn and the vertical transverse axis of the horn. This will cause the rollers to pass directly beneath the transverse center of the horn and move longitudinally thereof. The star wheel is so proportioned and mounted 85 as to cause the rollers to swing upwardly above the lower face of the horn. For this 90 purpose the arcuate block 20 is secured between the horn plates 19 and forms a track along which the rollers 25 move. The center of the arc of this block is the rotating 95 axis of the star wheel.

It is necessary to drive the star wheel and the feed chain 15 in synchronism, and for that reason a drive shaft 27 is provided. This shaft extends longitudinally of the bed plate 10 and is journaled within bearings 28. A 100 bevel gear 29 is fixed to this shaft, and is in mesh with a bevel gear 30 fixed upon a transverse shaft 31. Sprocket wheels 32 and 33 are mounted on this shaft. The sprocket wheel 32 carries a chain 34 which is led 105 around a driving sprocket 35 of the star wheel 22. The sprocket 33 carries a chain 110

36 which is led around a sprocket 37 secured to the standard 12 at the end of the horn. This sprocket is mounted upon a shaft 38 parallel to the shaft 13 and acts through 5 suitable transmission mechanism 39 to drive the sprocket 14 at the end of the horn in a reverse direction. Due to this transmission mechanism the lower run of the chain 15 will move in the direction of the arrow 10 —a—, and the star wheel 22 will move in the direction of the arrow —b—.

In operation of the machine, can bodies are formed and placed on the horn 17, thereafter being moved down until they are engaged by the flights 16 of the feed chain 15. The can bodies will then travel in the direction of the arrow —a—.

We will assume that the feed chain and the star wheel have been properly adjusted 20 and that they may move in synchronism. Reference to Fig. 1 will disclose the fact that the distance between the rollers 25 of the adjacent arms of the star wheel is greater than the length of a can body. This will 25 permit a can body to be moved along between these arms as their rollers engage the arcuate track 20. Attention is directed to the fact that the arcuate bearing face of the member 20 is recessed relative to the lower 30 edges of the plates 19 and the side members 21. This produces an arcuate channel into which the rollers pass, and will thus prevent radial movement of the horn. As the can A moves forward, radial arm B will move 35 from beneath the horn and radial arm C will travel along the arcuate face of the member 20 as it follows the can body A. A can body D will be following the radial arm C, and this will in turn be followed by the next 40 adjacent radial arm E. This sequence of operation will continue as the successive cans are fed along the horn and the star wheel rotates.

It will thus be seen that the structure here 45 disclosed provides simple means for continuously supporting a solder horn and insuring the cans may be fed therealong without interruption.

While we have shown the preferred form 50 of our invention, as now known to us, it will be understood that various changes might be made in the combination, construction, and arrangement of parts, by those skilled in the art, without departing from 55 the spirit of the invention, as claimed.

Having thus described our invention, what we claim and desire to secure by Letters Patent is:

1. In combination with a solder horn along 60 which can bodies may be fed, of means for supporting said horn comprising a star wheel having radial arms and adapted to be rotated about a fixed center below the horn, rollers mounted at the outer ends of said 65 arms a fixed distance from the center of the

star wheel and upon which the weight of the horn is successively disposed.

2. A machine for making cans, comprising a solder horn having an arcuate recess in the under face thereof, a star wheel rotating 70 beneath the horn with its arms successively moving along said arcuate face and receiving the weight of the horn, means for feeding cans along the horn, and means operating in synchronism therewith for rotating 75 the star wheel so that the arms thereof will successively support the horn between the cans moving therealong.

3. A machine for making cans, comprising a floating solder horn, can feed means moving parallel thereto, and adapted to feed cans 80 along the horn in equal spaced relation to each other, an arcuate track formed in the under face of the horn, a star wheel adapted to be rotated beneath the horn, and rollers 85 carried upon the ends of the star wheel arms for engaging said track.

4. A machine for making cans, comprising a floating solder horn, can feed means moving parallel thereto and adapted to feed the 90 cans along the horn in equal spaced relation to each other, an arcuate track formed in the under face of the horn, a star wheel adapted to be rotated beneath the horn, rollers 95 carried upon the ends of the star wheel, arms for engaging said track, and means for operating the feed mechanism and the star wheel in synchronism, whereby the rollers on the star wheel will successively engage the track and support the horn without interrupting the movement of the cans along the 100 horn.

5. A machine for making cans, comprising a floating solder horn, can feed means moving parallel thereto, and adapted to feed 105 cans along the horn in equal spaced relation to each other, an arcuate recessed track formed in the under face of the horn, a star wheel adapted to be rotated beneath the horn, and rollers carried upon the ends of the star wheel arms for engaging said track, and means for preventing lateral movement of the horn relative to the star wheel.

6. In a can making machine, a horizontally disposed horn comprising a pair of 115 spaced vertical plates, arcuate side plates secured to the outer faces thereof, and substantially conforming to the inner diameter of can bodies adapted to move along said horn, an arcuate track secured between said 120 vertical plates of the horn, and a star wheel formed with radial arms, and rollers on said arms adapted to successively move along the arcuate track as the star wheel rotates.

7. In a can making machine, a horizontally 125 disposed horn comprising a pair of spaced vertical plates, arcuate side plates secured to the outer faces thereof, and substantially conforming to the inner diameter of can bodies adapted to move along said 130

horn, an arcuate channel extending longitudinally of the horn and in the lower face thereof, a star wheel formed with radial arms disposed beneath the horn, and rollers, 5 one upon each arm, adapted to successively move along said channel and support the weight of the horn.

8. In a can making machine, a horizontally disposed horn comprising a pair of spaced vertical plates, arcuate side plates secured to the outer faces thereof, and substantially conforming to the inner diameter of can bodies adapted to move along said horn, an arcuate channel extending longitudinally 10 of the horn and in the lower face thereof, a star wheel formed with radial arms disposed beneath the horn, and rollers, one upon each arm, adapted to successively move along said channel and support the weight of the 15 horn, means for feeding cans along the horn 20

in equal spaced relation to each other, and operating in synchronism therewith for causing the can feed means and the arms to move in a manner to continuously support said horn.

9. In combination with a floating solder horn and a feed mechanism for feeding can bodies along the horn in equal spaced relation to each other, of means for supporting the horn comprising a starwheel having radial arms and adapted to rotate about a fixed center below the horn, rollers mounted at the ends of the arms at a fixed distance from the center of the starwheel and means for operating said starwheel and feed mechanism in synchronism whereby said rollers will engage the horn between cans being fed therealong and support the horn. 30 35

ARTHUR L. DUNCAN.
